assignors to The General Tire & Rubber Company, Akron, Ohio, a corporation of Ohio

Application November 30, 1935, Serial No. 52,395

6 Claims. (CL 154—14)

This invention relates to a method of and apparatus for splicing the ends of elongated uncured rubber bodies.

One of the objects of the present invention is to provide a new and improved method of splicing uncured bodies of rubber by means of which the ends of the body are easily and efficiently brought into adhering contact with each other.

Another object is to provide a splicing apparatus of new and improved construction in which means for cutting the uncured stock to predetermined length and means for efficiently joining the ends of the body are provided.

With the above and other objects in view the present invention consists in certain method steps and certain features of construction and combinations of parts to be hereinafter described with reference to the accompanying drawings and then claimed.

20 In the drawings, which show the invention in connection with the splicing of rubber tube stock,

Figure 1 is a view showing the step of cutting the tube stock to predetermined size.

25 Fig. 2 is a view showing the step of punching the tube to provide a valve stem opening.

Fig. 3 is a view similar to Fig. 2 showing the tube stock in supported position and showing the punched valve stem opening therein.

30 Fig. 4 is a view showing the positioning of the valve body on the tube over the opening.

Fig. 5 is a view showing the step of pressing the valve body into position in alignment with the opening of the tube.

35 Fig. 6 is a view showing the ends of the tube supported in a position to be clamped for joining the ends of the tube together.

Fig. 7 is a view showing the step of joining the ends of the tube together.

40 Fig. 8 is a fragmentary plan view showing the joined ends of the tube stock.

Fig. 8a is an enlarged fragmentary plan view of the splicer.

Fig. 9 is a plan view of the apparatus of the 45 present invention.

Fig. 10 is a vertical section taken approximately on the line 10—10 of Fig. 9.

Fig. 11 is an enlarged section taken approximately on the line 11—11 of Fig. 9.

50 Fig. 12 is a section taken approximately on the line 12—12 of Fig. 9.

Fig. 13 is a section taken approximately on the line 13—13 of Fig. 12.

55 Fig. 14 is a side elevation of the apparatus shown in Fig. 9.

Fig. 15 is an end elevation showing the tube cutting knife and the means for forming the opening for the valve body.

Fig. 16 is an enlarged section taken approximately on the line 16—16 of Fig. 15.

Fig. 17 is an enlarged fragmentary view partially in section showing the means for latching the punch used in forming the tube with a valve body opening.

Fig. 18 is a fragmentary top plan view showing 10 the two different positions of the punch and the valve body pressing means.

Fig. 19 is an enlarged view partially in section showing the valve body pressing means and the 15 punch.

Fig. 20 is a view similar to Fig. 19 showing the punch in its lower-most position.

Fig. 21 is a section taken approximately on the line 21—21 of Fig. 19.

Fig. 22 is a schematic showing of the hydraulic 20 means for operating the cutting blade and the valve body pressing means.

Fig. 23 is a side elevation of the tube splicing means showing the carriage in its retracted position and taken approximately on line 23—23 25 of Fig. 9.

Fig. 24 is a view similar to Fig. 23 but showing the carriage in its operative position.

Fig. 25 is an enlarged longitudinal section of the tube splicing means, when the carriage is in 30 its operative position, taken approximately on line 25—25 of Fig. 26.

Fig. 26 is a transverse section taken approximately on the line 26—26 of Fig. 25.

Fig. 27 is a section taken approximately on 35 the line 27—27 of Fig. 25.

Fig. 28 is a fragmentary plan view of the lower-most tube splicing jaws, portions of the same being shown in the section.

Fig. 29 is a plan view of the upper-most splicing 40 jaws.

Fig. 30 is a transverse section similar to Fig. 26 showing the jaws in their closed position.

Fig. 31 is a section taken approximately on the 45 line 31—31 of Fig. 25.

Referring to the accompanying drawings in which like numerals refer to like parts throughout the several views, the tube splicing apparatus includes a means for measuring and cutting the tube stock to the proper length, a means for mounting a rubber valve body on the tube stock and a means for joining the ends of the tube stock together.

The apparatus of the present invention in- 55

cludes a supporting table portion 1, in which the various mechanisms are mounted.

The first step in the operation is to measure and cut the uncured tubular rubber stock to size and for this purpose the table portion 1 is provided with a longitudinally extending guide block 2 having tapered sides as shown in Fig. 11, which carry a slidable gauge arm 3. A screw 4 is provided in the arm 3, which, when tightened against the guide block 2 clamps the arm in position. The guide block 2 may be provided with a calibrated scale 5 so that the arm 3 can be accurately set in the desired position. The arm 3 extends transversely of the table portion 1 and is parallel to the edge of one of the ends of the table portion 1.

Positioned at this end of the table portion 1 in alignment with the arm 3 is a plate 6, which is preferably of brass, and associated with this plate is a knife or cutter 7. The cutter 7 is inclined as shown in Fig. 12 but is arranged to be reciprocated in a vertical direction.

The cutter 7 is guided at its ends in vertical slots 8 which are formed in spaced up-right members 10 that extend upwardly from the end of the table portion 1 the up-right members 10 being formed on a member 10a, which is secured to the under side of the table portion 1. The cutter 7 is reciprocated by means of guided rod members 11 connected with the ends of the cutter and having rack teeth 12 thereon which mesh with pinions 13. The pinions 13 are mounted on a shaft 14, which is provided with an arm 15. The arm 15 is actuated by a rod 16, which is connected with a plunger rod 17 extending into a hydraulic cylinder 18, the plunger rod 17 having a plunger (not shown) for reciprocation within the cylinder 18. The cylinder 18 is provided with connections 19 and 20, which extend to a valve 21 diagrammatically shown in Figure 22, the valve 21 being connected with a pressure line 22.

In cutting the tube stock A to size, the arm 3 is set in the proper position corresponding to one-half the length to which the tube stock is to be cut and the tube stock is folded over upon itself as shown in Figure 1 with the folded end abutting the arm 3 and the ends thereof projecting over the shear plate 6 at the end of the table portion 1. The valve 21 is then operated which causes the edge 8 of the cutter 7 to travel toward the plate 6 and cut off the ends of the tube stock projecting beyond the plane of the cutter edge 8.

If desired, the cutter may be heated by heating coil 23 secured thereto as shown in Figure 12. A stripper plate 24 may be provided to prevent the severed ends of the tube stock from clinging to the cutter.

The next step in the tube forming operation is to provide the tube stock A with a rubber valve body B in registration with an opening C to be formed in the tube stock. For this purpose an inverted U-shaped support 25 is provided. This support is secured to the member 10a, and is provided with an arm 26 extending over the table portion 1 as shown in Figures 9 and 14. The arm 26 is provided with a punch block 27 in its uppermost surface, the punch block preferably being of brass.

The operation of providing the tube stock with the valve B consists in first punching the opening C (Figure 4), and then pressing the valve B in place. In order to do this, one end of the tube stock A is slid over the arm 26 as shown in Figure

2, so that one wall of the tube stock overlies the punch block 27.

The apparatus employed comprises a punch 28 and a valve pressing tool 30, both of which are supported on the opposite ends of a horizontal member 31. The member 31 is pivoted intermediate its ends on a vertical pivot pinion 32, which is carried by a vertically movable arm 33, the arm 33 being guided for vertical movement in a dove-tail 34, which is secured to the table portion 1. The arm 33 is moved by a vertical plunger rod 35, which extends through the table portion 1 and into a fluid pressure cylinder 36 the rod 35 having a plunger (not shown) which slides within the cylinder 36. The cylinder 36 has lines or conduits 37 and 38 which lead to a suitable valve 39 shown in Figure 22, the valve being connected by a conduit 40 with the main pressure line 22.

The punch 28 is in the form of an inverted frusto-conical shell carried by the vertical rod 41, arranged to slide in a sleeve 42 carried by the pivoted member 31. The sleeve 42 is counterbored at its lower end at 44 to receive a coil spring 43 surrounding the rod 41, one end of the spring 43 being in abutting engagement with a stop collar 45 secured to the rod 41 and the opposite end of the spring in an abutting engagement with the bottom of the counterbore 44 as shown in Figures 19 and 20. The upper end of the sleeve 42 is provided with a counterbore 44a which receives a spring 43a that surrounds the rod 41, the upper end of the spring 43a being in engagement with guide keys 41a carried by the rod 41. The spring 43a is of greater strength than the spring 43. The upper end of the rod 41 is provided with ratchet teeth 46, and the member 31 is provided with a pivoted lever 47, one end of which is arranged to engage the ratchet teeth 46 and hold the rod 41 in its upper-most position as shown in Figure 19 with the spring 43 compressed. A compression spring 47a is arranged between the sleeve 42 and the lower end of the lever 47 to resiliently urge the lower end of the lever outwardly to hold the upper end 48 of the lever in engagement with the ratchet teeth.

The valve pressing tool 30 has a resilient part 49 at its lower surface and is hollow, as shown at 49a in Figure 19, to receive the stem portion of the valve body B. The tool 30 is secured to a vertical rod 50, which is fixed in any suitable manner to the horizontal pivot member 31, as shown in Figures 19 and 20. The arm 31 is provided with a tension spring 31a, which acts to hold it in either of its pivoted positions.

In forming the opening C in the tube stock A the member 31 is pivoted to a position limited by an adjustable stop 51, shown in dotted outline in Figure 18, whereby the punch 28 is in alignment with the punch block 27 and the lower end of the lever 47 is pressed inwardly toward the sleeve 42 to disengage the upper end 48 of the lever 47 from the ratchet teeth 46. The pressure of the spring 43 then drives the rod 41 and punch 28 downwardly with a force sufficient to cause the punch 28 to travel through the wall of the tube stock and form the opening C. The compression pressure of the spring 43a being greater than that of spring 43 then slightly raises the punch 28 so that it clears the surface of the table and so that the end 48 of the lever 47 will be engaged by the ratchet teeth 46 and hold the rod 41 in a slightly raised position.

The arm 31 is then pivoted in a counterclock-

wise direction, as viewed in Figure 18 to the position shown in solid outline, this position being predetermined by an adjusting screw 52, to align the valve pressing tool 30 over a pin 28, which is carried by a plunger 28a raised slightly above the surface of the table by a spring 28b. The tube stock is then moved so that the punched opening C surrounds the plunger 28a as shown in Figure 3. The valve body B which has a circular flange, the surface of which is preferably tacky, is positioned over the opening C as shown in dotted outline in Figure 4, the pin 28 extending into the opening in the valve body to hold the valve body in centered position with respect to the opening C.

The operator next operates the valve 38 which allows the fluid under pressure to enter the upper end of the cylinder 36 through the conduit 37 and drive the plunger downwardly, causing the tool 30 to travel downwardly with sufficient force to firmly press the flange of the valve body B into firm, intimate contact with the tube stock. Because of the fact that the tube stock is unvulcanized and the surface of the flange of the valve body is tacky, the valve body will securely adhere to the tube stock.

During the downward travel of the member 31, the punch 29 travels through a sleeve 58 carried by a supporting bracket 59 at one side of the arm 26, as shown in Figures 9 and 14, and at a predetermined point in its travel the collar 45 engages the sleeve 58 which holds the rod 41 against further movement during the remainder of the travel of the arm 33, whereby the spring 35 43 will be compressed and the latching means described will hold the rod 41 in its upper-most latched position. The tube stock A is now in condition to have the ends thereof joined together. The end faces of the tube stock are tacky as a result of the severing operation by the knife or cutter 7 and because of the fact that the tube stock is unvulcanized.

The apparatus for joining the ends of the tube stock together includes a pair of normally spaced lower jaws 53 each having a series of small upper projecting teeth 54 at its inner edge, and a pair of normally spaced upper jaws 55 each having a series of small downwardly projecting teeth 56 at its inner edge, as shown in Figures 26 to 29.

Mounted above the table portion 1 is a spaced horizontal plate 57 such as shown in Figures 14 and 25.

The plate 57 is formed with a recess 60 on its upper surface across its forward end, as seen in Figures 25, 27, 28, and 30, to the bottom of which spaced guide blocks 61 are secured the guide blocks 61 having their upper surfaces flush with the surface of the plate 57 and having inwardly extending tongues 62 spaced above the bottom of the recess 60, as shown in Figure 30. Also mounted in the recess 60 inwardly of the block 61 are a pair of spaced sliding blocks 63 having grooves 64 receiving the tongues 62 the blocks 63 being urged apart by a spring 65. The slide blocks 63 are also provided with portions 66 extending upwardly above the plate 57, the outer lateral faces 67 of these portions 66 being tapered downwardly and outwardly, as shown in Figure 30, to provide cam surfaces. Also mounted on the plates 57 outwardly of the upstanding portions 66 are a pair of upstanding portions 68 having transverse slots 69 therein, as shown in Figures 23 and 24.

The plate 57 is provided with a number of separated recesses or depressions 70, each of which contains a bearing plate 71, and a number of small balls 72. Seated over the plate 55 and in engagement with the balls 72 are a pair of slide plates 73 which are slotted at 74 to extend around the upstanding portions 68. These plates 73 are each provided at their inner edges, as shown in Fig. 28, with a series of slidably interfitting fingers 75 along their inner edges. The plates 73 are secured by screws 76 to the slide blocks 63 as shown in Fig. 30.

Each of the plates 73 is also provided with a longitudinally extending groove or channel 77 in its upper surface and these channels 77 receive 15 the lower jaws 53, the teeth 54 of the jaws 53 being disposed over the interfitting fingers 75 as shown in Figs. 29 and 30.

At the rearward ends, as shown in Figs. 26 and 28, the side plates 73 are provided with upwardly extending portions 78, the outer lateral faces 79 of which are tapered downwardly and outwardly to provide cam surfaces. The portions 78 have apertures therein through which a rod 80 extends, the ends of the rod 80 being supported by brackets 81 secured to the plate 57. Surrounding the rod 80, and disposed between the portions 78 is a coil spring 82 which functions with the spring 65 to resiliently urge the slide plates apart and normally space the lower jaws 53 as shown in Figs. 27 and 28.

Mounted at one side of the table portion 1 are a pair of upstanding brackets 83, each of which is provided at the inner sides with a series of upper anti-friction rollers 84, and a series of lower anti-friction rollers 85 spaced from the rollers 84. A slidable carriage 86 is mounted between the series of upper and lower rollers, horizontal anti-friction rollers 87 being provided at the forward and rearward ends of the brackets 83 for engaging the sides of the carriage 86.

As shown in Figs. 25, 26, and 27, the carriage 86 is provided with longitudinally spaced transversely extending recesses 88, extending vertically therethrough, and extending between the walls of each recess 88 are spaced webs 89. The webs 89, however, as shown in Figs. 25 and 26, extend only part way down the recesses 88.

Disposed within the recesses 88 below the webs 89 are vertically movable blocks 90. Each block 90 is normally in an uppermost position adjacent the lower edge of the webs 89 and is held in such position by bolts 91 threaded therein and extending upwardly through certain of the webs 89 and provided at their upper ends with heads 92, coil springs being provided around the projecting ends of the bolts 91 and between the heads 92 and webs 89.

Extending through the webs 89 in each recess 88 is a shaft 94. Each shaft has secured thereto a pair of cams 95 which engage with the blocks 90. The shafts 94 are provided with portions 96 extending upwardly between the webs 89 and above the carriage 86, as shown in Figs. 23, 24, 25 and 26, and the upper ends of these portions 96 are interconnected by an adjustable link 97. The foremost portion 96, as shown in Fig. 25, is connected by a link 98 with an actuating lever 99 which is pivoted by means of a pin 100 to the forward end of the carriage 86. By actuating the lever 99 the blocks 90 through the medium of the cams 95 are caused to travel downwardly.

Each of the blocks 90 is provided with a downwardly presenting transverse recess 101 which is 75

- of dove-tail shape in cross-section, as shown in Fig. 25, and slidably mounted in each recess is a pair of spaced slide blocks 102 which are resiliently held apart by coil springs 103, as shown in Fig. 26. The blocks 90 and slide blocks 102 are provided with opposed recesses 104, and between plates 105 in the bottoms of these recesses are a number of small balls 106 which provide for relatively free movement of the blocks 102 in the recesses 104.
- The blocks 102 support a pair of spaced plates 107 which, as shown in Fig. 29, are similar to the lower plates 73 and which are provided at their inner edges with slidable interfitting fingers 108.
- The plates 107 are longitudinally recessed and carry the upper jaws 55, as shown in Figs. 26, 27, and 29.
- The upper jaws 55 are arranged to be moved toward each other and the lower jaws 53 are arranged to be moved toward each other, by a single means when the carriage 86 is extended to the position shown in Figs. 24 and 25. In order to accomplish this, the carriage is provided with a pair of forward vertically movable pins 109, one for the forward end of each plate 73 and a pair of rearward vertically movable pins 110, one for the rearward end of each plate 73. These pins are slidably mounted in vertical openings 111 in the carriage, the upper ends of which are counterbores 112 to receive coil springs 113 which surround the pins and engage the bottom of the counterbores and the heads 114 of the pins. Also, the pins are provided with tapered cam surfaces 115 at their lower ends to engage with the cam surfaces 67 and 79 of the upstanding portions 66 and 78, respectively. Mounted at the rearward end of the carriage 86 is a horizontal shaft 116 having cams 117 thereon which engage the heads of the rearward pins 110.
- Also, mounted at the forward end of the carriage, as shown in Fig. 25, is a horizontal shaft 118 having cams 120 thereon which engage the heads of the forward ends 109. The coil springs 113 cause the heads 114 of the pins 109 and 110 to resiliently engage the cams 117 and 120.
- The shafts 116 and 118 are provided with levers 122 which are interconnected by an adjustable link 123 and the forward lever 122 is connected by a link 124 to a lever 125 pivoted to the forward end of the carriage 86 as shown in Figs. 23, 24, and 25.
- As previously set forth, the carriage 86 is normally in the retracted position, as shown in Fig. 23. The carriage has a pair of rearwardly extending portions 126 which are interconnected by a transverse portion 127. The portion 127 is provided with spaced adjusting screws 128 which, when the carriage is moved to the operative position shown in Fig. 24, engage with the supports 87a for the rollers 87 and limit the forward movement of the carriage.
- The carriage 86 is also provided with side portions 129 having forwardly projecting fingers 130 at their forward ends which, when the carriage 86 is in the operative position shown in Fig. 24, fit within the slots 68 of the portions 66 and prevent upward movement of the forward end of the carriage. The portions 129 engage with the rollers 84, 85 and 87 to guide the carriage 86.
- In joining the ends of the tube stock A together to form a completed tube, the tube stock A is disposed underneath the plate 57, then the two ends of the tube stock are placed over the lower jaws 53, with the transverse ends abutting each other 75 in a plane midway between the teeth 54 of the

lower jaws 53, as shown in Fig. 6, and pressed downwardly so that the teeth 54 are extending into the unvulcanized tube stock and hold the ends together.

The carriage is then moved to its operative position shown in Fig. 25, and the operator first pulls the lever 99 downwardly, which causes the plates 107 to move downwardly between the inner faces of the upstanding portions 66 and 78, as shown in Fig. 30, and clamp the ends of the tube stock; the teeth 54 and 56 of the jaws being caused to become deeply embedded in the tube stock adjacent the severed ends. The cams 96, when the lever 99 is swung to its lowermost position, as shown in Fig. 24, lock the plates against upward movement and hold them in their clamping position.

The operator then pulls the lever 125 downwardly to the position shown in Fig. 24, and this causes the pins 109 and 110 to move downwardly and the cam surfaces of these pins engage the inclined cam faces 67 and 79 of the upstanding portions 66 and 78 respectively, so that during the continued downward movement of the pins 109 and 110 the portions 66 and 78 simultaneously move the jaws 53 toward each other and the jaws 55 toward each other. This movement of the jaws 53 and 55 tends to compress the material of the tube stock between the embedded teeth and severed ends which brings the severed ends into more intimate contact with each other. The compressive action exerts considerable pressure against these severed ends which causes them, because of their tacky surfaces and the character of the unvulcanized material, to continuously adhere to each other, and the interfitting fingers on the respective plates 73 and 107 prevent the tube material from bulging or moving outwardly at the region between the jaws, thereby providing for a better union between the abutting ends of the tube material.

The operator then raises the lever 99 which allows the upper jaws 55 to move upwardly away from the tube stock and relieve the tube stock of the clamping pressure. The operator next raises the lever 125 which allows the lower slide plates 73 to return to their normally spaced relation and withdraw the teeth 54 from the tube stock. Finally, the carriage is moved to its retracted position and the tube is removed from the apparatus.

The tube may then be transferred to a suitable vulcanizing heater for vulcanization.

Because of the fact that the tube is spliced when it is unvulcanized, the teeth which are embedded in the tube while it is clamped, immediately adjacent the line of splicing, function to force the material comprising the tube toward the line of splicing and actually compresses the same, and this, together with the tackiness of the unvulcanized material where it was severed and the confining of the material at the end of splice against outward movement, provides an efficient, continuous union between the ends of the tube, which will hold these ends securely together during the subsequent vulcanizing operation.

The jaws instead of being formed with the series of projecting teeth may be provided with narrow ribs at their adjacent edges which will function the same as the teeth in providing for increased clamping action immediately adjacent the line of splicing.

While we have described the apparatus in connection with the splicing of tubes it is to be understood that it is applicable to the splicing

of other elongated uncured rubber bodies, such as for example, tire flaps.

Furthermore, it is to be understood that the particular form of apparatus shown and described, 5 and the particular procedure set forth, are presented for purposes of explanation and illustration and that various modification of said apparatus and procedure can be made without departing from our invention as defined in the appended 10 claims.

What we claim is:

1. The method of splicing the end portions of elongated uncured rubber bodies which comprises severing each end portion to provide it with a 15 clean-cut tacky end surfaces, mating said end surfaces with each other, clamping each of said end portions immediately adjacent to the line of mating of said end surfaces, and longitudinally compressing the portions of said end portions which 20 lie between the zones of clamping while confining said contacting end portions against outward lateral movement.

2. The method of splicing the end portions of elongated uncured rubber bodies which comprises severing each end portion to provide it with a 25 clean-cut tacky end surface normal to each side surface thereof, engaging said tacky end surfaces with each other, subsequently clamping said body and reducing the cross sectional area thereof at 30 opposite sides of the line of engagement of said end surfaces but at narrow localized zones closely adjacent said line of engagement, confining the portion of said body between said clamping zones and then longitudinally compressing the 35 confined portion of the body including said engaged end surfaces and which is disposed between said localized zones of clamping.

3. The method of splicing the end portions of elongated uncured rubber bodies which comprises severing each end portion to provide it with a 40 clean-cut tacky end surface normal to each side surface thereof, engaging said tacky end surfaces with each other, subsequently clamping said body at opposite sides of the line of engagement of said 45 end surfaces but at narrow localized zones closely adjacent said line of engagement, and then

longitudinally compressing that portion of the body including said engaged end surfaces and which is disposed between said localized zones of clamping while confining the material comprising said portion against outward lateral movement. 5

4. The method of joining the ends of an elongated rubber tube together, which comprises severing each of said ends to provide it with a clean-cut tacky end surface normal to each side surface 10 thereof, aligning and mating said end surfaces with each other, subsequently clamping each of said ends immediately adjacent to the end surface thereof, and longitudinally compressing that portion of the tube including the mated end surfaces and which lies between the zones of clamping, 15 while preventing lateral flow of rubber in said portion of the tube between the zones of clamping.

5. The method of joining the ends of an elongated rubber tube together, which comprises severing each of said ends to provide it with a clean-cut tacky end surface normal to each side surface thereof, aligning and mating said end surfaces with each other, subsequently clamping 25 each of said ends with increased clamping pressure to reduce the cross sectional area thereof over a narrow zone immediately adjacent to the end surface thereof, confining that portion of the tube including the mated end surfaces and which 30 lies between the zones of clamping, and subjecting the confined portion to longitudinal pressure.

6. The method of joining the ends of an elongated rubber tube together, which comprises severing each of said ends to provide it with a clean-cut tacky end surface normal to each side surface thereof, aligning and mating said end surfaces with each other, subsequently clamping each of said ends immediately adjacent to the end surface thereof, and longitudinally compressing that 35 portion of the tube including the mated end surfaces and which lies between the zones of clamping while holding said portion against outward lateral movement. 40

MAX ENGLER. 45

WALTER J. BRETH.
